UNITED STATES PATENT OFFICE.

CALVIN C. WOOLWORTH, OF NEW YORK, N. Y., ASSIGNOR TO WOOLWORTH & GRAHAM, OF SAME PLACE.

WATER-MARK ON PAPER AND DEVICE FOR PRODUCING THE SAME.

SPECIFICATION forming part of Letters Patent No. 248,001, dated October 4, 1881.

Application filed September 5, 1881. (No model.)

To all whom it may concern:

Be it known that I, CALVIN C. WOOLWORTH, a citizen of the United States, residing at New York, in the county of New York and State of New York, have invented new and useful Improvements in Water-Marks on Paper and in Devices for Producing the Same, of which the following is a specification.

This invention relates to improvements in water-marks on paper, whereby letters and figures and parts thereof, of which said water-marks consist, have not their superficial area limited, as has heretofore been the case, to that of about one-half of the diameter of such wire, or several wires, as it has been possible to employ in forming figures and letters upon the "dandy-roll" of the paper-machine, the object being to provide means for producing watermarked letters and figures upon paper in which the characters constituting the watermark have a full flat surface from edge to edge thereacross, as well upon the widest as upon the narrowest parts of said characters.

In the drawings forming part of this specification, Figure 1 illustrates the dandy-roll of a paper-machine constructed with watermarking appliances according to my invention. Fig. 2 illustrates the water-mark as it appears upon a sheet of paper when produced according to my invention.

In the drawings, *a a* represent water-mark letters on a sheet of paper, *c*.

b is a water-mark figure, also on said sheet. *d* is a dandy-roll, and *e* indicates the watermark-producing letters and character on said dandy-roll.

Instead of forming water-mark letters and

devices on the dandy-roll by suitably attaching wire thereto bent to form letters and other objects, as is ordinarily done, I cut my water-mark devices *e* from sheet metal or other suitable material and secure them upon, or partially let them into, the face of said roll, as shown in Fig. 1, causing said devices *e* to be so bent as to conform to the cylindrical surface 45 of said roll.

Thus a great variety of designs may be watermarked on paper not heretofore attainable when limited to such only as could be formed from wire, and thus producing full-faced watermark letters *a* upon paper, and such full-faced figures as the anchor *b* and other designs, all the parts of said letters and figures which in printing would be made full-faced for the sake of symmetry and broad effects being 55 producible by water-mark upon paper by the use of my improvements.

What I claim as my invention is—

1. The within-described improvement in the art of watermarking paper, which consists in 60 forming thereupon letters and figures whose various parts have full water-mark depressions from edge to edge across the face thereof, in contradistinction to outlined letters and figures, substantially as set forth.

2. The within-described improved watermarking devices, which consist of the dandy-roll *d*, having full-faced letters or figures, or both, secured to the cylindrical surface thereof, substantially as and for the purpose set forth. 70

CALVIN C. WOOLWORTH.
